UNITED STATES PATENT OFFICE.

NATHAN ALLEN GIBBONS, OF MARTINS FERRY, OHIO.

CAN-HEADING DEVICE.

1,355,465.

Specification of Letters Patent.

Patented Oct. 12, 1920.

Application filed November 15, 1919. Serial No. 338,209.

To all whom it may concern:

Be it known that I, NATHAN ALLEN GIBBONS, a citizen of the United States of America, and resident of Martins Ferry, county of Belmont, and State of Ohio, have invented certain new and useful Improvements in Can-Heading Devices, of which the following is a specification.

This invention relates broadly to can heading devices, and more particularly to a tool for attaching heads or covers upon cans, pails, drums and like receptacles.

The primary object of the invention is to provide a simple and inexpensive hand tool whereby the lugs provided annularly on the covers of cans, pails, or drums may be conveniently closed or clenched over the upper end beads or rolls of the latter.

A further object is to provide a tool of the character mentioned by means of which the head or cover is held firmly seated upon the can during the lug-turning operation and whereby the turning of the lugs into interlocking relation to the bead or roll of the can is effected without producing buckling of the metal.

With these and other objects in view, the invention resides in the features of construction, arrangement of parts and combinations of elements which will hereinafter be fully described, reference being had to the accompanying drawings, in which—

Figure 1 is a side elevation of the invention, showing the lug-turning member depressed to a position overlying the tongs members;

Fig. 2 is an under side elevation of the same;

Fig. 3 is a side elevation illustrating the application of the invention, the lug-turning member being shown in its initial operating position; and—

Fig. 4 is a similar view showing the lug-turning member in its final operating position.

Referring to said drawings, in which like designating characters distinguish like parts throughout the several views—

1 and 2 indicate, respectively, the upper and lower jaws of a pair of tongs constituted by crossed members 3 and 4 which are pivotally connected at the crossing point, as shown at 5, and which have their rear end portions shaped to form handles 6 and 7.

55 The lower jaw 2 has a broad body which is of bifurcated form to provide two similar widely-separated upwardly and for-

wardly curved or inclined claws 8. The upper jaw 1 has a width materially less than that of the bifurcation of the lower jaw 60 and is provided on its under face with a transversely extending concave channel 9 having a curvature corresponding to that of the surface upon which said jaw is to rest when the tool is in use. 65

Pivottally mounted upon the upper jaw 1 is the front end portion of a lug-turning member which comprises a curved jaw 11 having a beveled lip 12 and a handle 13. The jaw 11 has a width approximating that 70 of the bifurcation in the jaw 2 and is designed to have its lip 12 lie within said bifurcation when the parts occupy the relative positions shown in Figs. 1 and 2. Said jaw 11 has provided therein rearward of the 75 lip portion 12 thereof a substantially rectangular hole or aperture 14 through which the jaw 1 projects. A transverse channel 15 having a curvature corresponding to that of the channel 9 of the jaw 1 is provided in 80 the outer face of the jaw 11, as shown.

A retractile coil spring 16 has one end attached to a pin or stud 17 fixed upon a side of the jaw 11 adjacent to the lip 12 and its opposite end attached to a pin or stud 18 85 fixed at a suitable point on the corresponding side of the jaw 1, said spring being designed to normally hold the lug-turning member in the retracted position shown in Fig. 3. 90

The can or pail 19 to which the cover 20 is to be applied by means of the tool described has an annular roll or bead 21 formed at its upper edge, said roll or bead being ordinarily disposed in inclosing relation to a reinforcing wire 22. Said cover 20 is preliminarily formed with its outer edge portion bent upward from the plane of its body and is then curved outward and downward, as shown in Fig. 3, to form a 100 downwardly facing annular channel adapted to receive snugly therein the roll or bead 21 of the receptacle. Provided on the said outer edge portion is a plurality of relatively spaced vertical tongues or lugs 23. 105

The cover 20 being seated upon the can or pail in the position shown in Fig. 3, the tool constituting the present invention is applied for turning the depending lugs 23 into closely underlying, or clenched, relation to 110 the bead or roll 21 for firmly securing said cover in place, the upper jaw 1 of said tool being disposed in overlying seated relation to said bead or roll with the latter received

in the channel 9 thereof, and the claws 8 of the lower jaw 2 being disposed against the body of the receptacle with their points closely engaging the under side of said bead 5 or roll. With said jaws firmly held in the position stated, the handle 13 of the member 10 is drawn back, turning said member on its pivotal mounting against the tension of the spring 16, until the jaw 11 thereof assumes the position shown in Fig. 4. In so moving forward, as is obvious, the edge of the lip portion 12 of said jaw 11 engages and turns the depending lug 23 into closely underlying relation to the bead or roll 21.

15 As is apparent, the form, shape and relative arrangement of parts of the structure herein described might be varied to a considerable extent without departing from the spirit or scope of the invention as defined in 20 the appended claims.

What is claimed is—

1. A tool of the character described, comprising a pair of tongs, of which one jaw is bifurcated and the coacting jaw has a width 25 materially less than that of the bifurcation of the first mentioned jaw, and a member pivotally mounted on the second mentioned jaw and having a jaw adapted to coöperate with said second mentioned jaw, said member being provided with an aperture located rearward of its jaw and having the second mentioned jaw projected through said aperture.

2. A tool for closing or turning covers on 35 the rim beads of cans, pails, or drums, comprising a pair of tongs of which one jaw is designed to seat upon the top of the bead-receiving portion of the cover, and the opposite jaw is formed with a pair of claws 40 and with a bifurcation between said claws, said claws being designed to engage the under side of a bead adjacent to the wall of the can, pail, or drum, and a lug-turning member pivoted upon the first mentioned jaw, 45 said member having therein an aperture through which said first mentioned jaw projects, said member having a jaw located forward of said aperture designed to be advanced into coöperating relation to said first 50 mentioned jaw for turning a depending lug of said cover into underlying clenched relation to the rim-bead of the can, pail, or drum.

3. A tool for closing or turning covers on 55 the rim beads of cans, pails, or drums, comprising a pair of tongs of which one jaw is designed to seat upon the top of the bead-receiving portion of the cover, and the opposite jaw is formed with a pair of claws and with a bifurcation between said claws, 60 said claws being designed to engage the under side of a bead adjacent to the wall of the can, pail, or drum, and a lug-turning member pivoted upon the first mentioned jaw, said member having therein an aperture through which said first mentioned jaw

projects, said member having a jaw located forward of said aperture designed to be advanced into coöperating relation to said first mentioned jaw for turning a depending lug of said cover into underlying clenched 70 relation to a rim-bead of the can, pail, or drum, the jaw of said lug-turning member having a width approximating that of the bifurcation in the second mentioned jaw and being movable into and out of said bifurcation. 75

4. A tool for turning or closing covers on the rim beads of receptacles, comprising a pair of tongs of which the lower jaw has a relatively greater width than the upper jaw 80 and is bifurcated, forming a pair of widely separated claw-like members, the upper jaw having a transverse channel in its under face, and a lever pivotally mounted upon said upper jaw and having a jaw designed 85 to act outwardly with respect to an object held by the jaws of said tongs.

5. A tool for turning or closing covers on the rim beads of cans, pails, or drums, comprising a pair of tongs of which the lower 90 jaw has a relatively greater width than the upper jaw and is bifurcated, forming a pair of widely separated claw-like members, the upper jaw having a transverse channel in its under face, and a lever pivotally mounted 95 upon said upper jaw and having an outwardly facing jaw on its front end, the last mentioned jaw having a width approximating that of the bifurcation in the lower jaw and operable into and out of said bifurcation, 100 said lever being adapted for actuation for forcibly thrusting its jaw forward with respect to an object grasped by the jaws of said tongs.

6. A tool for turning or closing covers on 105 the rim beads of cans, pails, or drums, comprising a pair of tongs of which the lower jaw has a relatively greater width than the upper jaw and is bifurcated, forming a pair of widely separated claw-like members, the 110 upper jaw having a transverse channel in its under face, and a lever pivotally mounted upon said upper jaw and having an outwardly facing jaw on its front end, the last mentioned jaw having a width approximating 115 that of the bifurcation in the lower jaw and operable into and out of said bifurcation, said lever being adapted for actuation for forcibly thrusting its jaw forward with respect to an object grasped by the jaws of 120 said tongs, and means normally holding said lever in a position in which its jaw is withdrawn from coöperative relation to the jaws of said tongs.

In testimony whereof, I affix my signature 125 in presence of two subscribing witnesses.

NATHAN ALLEN GIBBONS.
